CARTON FORMING MACHINE

Louis Veyret, Neuilly-sur-Seine, and Georges
Geffroy, Paris, France, assignors to La Cello-
phane, Paris, France, a French company

Application December 31, 1947, Serial No. 794,981
In France October 21, 1944

Section 1, Public Law 690, August 8, 1946
Patent expires October 21, 1964

2 Claims. (Cl. 93—51)

1

This invention relates to box forming machines and more particularly to a machine for folding and forming open top cartons for food products or the like.

An object of the invention is to provide a machine for so folding the blanks that in the folded carton no open seams which require sealing extend below a predetermined level which corresponds to the level to which the carton is to be filled.

Another object is to provide a machine of the above type which forms the carton in a single stamping operation.

Another object is to provide a machine of the above type which is automatic in operation.

Another object is to provide a machine of the above type having novel and improved details of construction and features of operation.

Various other objects and advantages will be apparent as the nature of the invention is more fully disclosed.

In accordance with one embodiment of the invention, the machine includes a forming plate adapted to receive the flat blanks, which is provided with a central, generally rectangular opening having an area corresponding to the bottom of the carton and having a pair of triangular extensions at each end for folding the end flaps. A piston conforming in section to the bottom of the carton forces the blank through the plate opening to start the folds. Side plates disposed along the path of the piston form the opposite smooth side walls of the carton and a series of guiding and folding members arranged along the path of the piston in the plane of the ends of the 35 carton serve to fold and form the end flaps as the blank is advanced past the various members. Sealing means, such as heated rollers, are provided for sealing the end seams of the carton before the finished carton is removed from the 40 piston.

Although the novel features which are characteristic of this invention are pointed out more in detail in the claims, the nature of the invention will be better understood by referring to the following description, taken in connection with the accompanying drawings, in which a specific embodiment thereof has been set forth for the purpose of illustration.

In the drawings:

Fig. 1 is a perspective view of the finished carton;

Fig. 2 is a top plan view of the forming plate with a flat blank thereon;

Fig. 3 is a vertical transverse section taken 55

2

along the line 3—3 of Fig. 2 showing the end folding, forming and sealing members;

Fig. 4 is a vertical longitudinal section taken along the line 4—4 of Fig. 2;

5 Fig. 5 is a partial horizontal section taken along the line 5—5 of Fig. 3;

Fig. 6 is a side elevation of a machine embodying the present invention adapted for hand operation;

10 Fig. 7 is a top plan view thereof;

Fig. 8 is a detail view of a sealing roller;

Fig. 9 is a top plan view of a machine embodying the present invention designed for automatic operation;

15 Fig. 10 is a side elevation of a portion of the machine of Fig. 9;

Figs. 11 and 12 are detail views illustrating different positions of the forming piston; and

20 Fig. 13 is a section on an enlarged scale taken on the line 13—13 of Fig. 11.

Referring to the drawings, the carton is formed from a rectangular blank A of paper or cellulosic sheet material such as cellophane or the like which may have heat sealing characteristics.

25 The folded carton is shown in Fig. 1 as comprising flat sides 10, ends 11, and a bottom 12. Each end 11 is formed by an upwardly folded bottom flap 13 having a top edge 14 and a pair of side flaps 15 and 16 which are folded over the bottom flap 13 and overlap to form a seam 17 which is secured by a suitable adhesive. The top of the carton is open to receive the food or other products to be incorporated therein. The carton contains no seams that require sealing below the top edge 14 of the bottom flap 13. Hence it is made liquid-tight to this point by the manner in which it is folded. The remainder of the sides and ends are folded inwardly to close the top of the package after it has been filled to the line 14.

The principles of operation of the machine are illustrated in Figs. 2 to 5. Referring to these figures, the machine is shown as comprising a flat, rectangular forming plate 20 on which the sheet A is placed. The plate 20 is provided with a central opening 21 defined by straight parallel side edges ab and ef spaced apart to conform to the width of the carton, and a pair of trapezoidal edges bcde and fgha at the respective ends with the edges cd and gh spaced to conform to the length of the carton. A pair of flat vertical side brackets 23 are disposed beneath the plate 20 in the plane of the edges ab and ef. A pair of vertical inverted U-shaped folding members 25 are attached to the plate 20 and are formed with short upper surfaces 26 in the plane of the top

of the plate 20 and having edges forming the edges *cd* and *gh* above mentioned, with inclined surfaces 27, and with vertical surfaces 28 which are spaced from the brackets 23 to provide clearance for the passage of the end flaps 15 and 16. Beneath each member 25 a pair of triangular folding members 30 are provided, which are secured to the respective brackets 23. The triangular members 30 have inclined top edges 31 which project across the ends of the carton from opposite sides and are curved to form a somewhat flattened cup as shown in Fig. 5. The members 30 may be formed as extensions of the brackets 23 or may be attached thereto. Beneath the members 30 are mounted rollers 33 and 34 which are journaled in the brackets 23 and are adapted to seal the seams 17.

A piston 35 having a cross section corresponding to the interior of the folded carton is adapted to slide vertically through the opening 21 between the side edges *ab* and *ef* and the end edges *cd* and *gh* of the plate 20. The piston 35 is shown as having an operating handle 36.

In the operation of this device, the flat sheet A is placed upon the plate 20, as shown in Fig. 2, and the piston 35 is pushed downwardly to force the sheet through the opening 21. As the sheet passes downwardly through this opening, the edges *ab* and *ef* form the sides 10 which are folded upwardly and smoothed by the side brackets 23. At the same time, the end portions of the sheet are folded upwardly by the edges *cd* and *gh* to form the bottom end flaps 13 and the edges *bc*, *de*, *fg* and *ha* initiate the folding of the end flaps 15 and 16 which then extend outwardly from the ends of the carton. As the piston 35 advances downwardly past the members 25, the flaps 13 are folded upwardly into place and the end flaps 15 and 16 pass downwardly between the edges 28 and the brackets 23. As the piston continues its advance, the triangular members 30 engage the respective end flaps 15 and 16 and fold the same over successively to form the ends of the carton as indicated in Fig. 1. As the piston 35 advances further, the carton passes downwardly with the seams 17 of the folded flaps 15 and 16 engaging the rollers 33 and 34. In the event that the sheet A is provided with adhesive 38 at the seam areas, as indicated in Fig. 2, the rollers exert pressure on the folded flaps to seal the seams. In the event that the sheet A is provided with a thermoplastic adhesive, the rollers are heated to exert heat and pressure against the folded flaps so as to heat seal the seam as the carton passes the rollers. The downward movement of the piston 35 is continued until the entire carton passes the rollers and can be removed from the bottom of the piston, after which the piston may be retracted and the forming operation repeated.

In the hand-operated machine, shown in Figs. 6 and 7, a supporting frame 40 is provided, carrying a pair of guide rods 41 which are mounted in bosses 42 and 43 secured to the frame and are inclined to the vertical as shown. The frame carries a supply table 44 on which the blanks are stacked. The supply table 44 is mounted adjacent the forming plate 20 above mentioned. The plate 20 is mounted on a bracket 45 and lies in a plane perpendicular to the guide rods 41. The piston 35 is carried by an arm 46 mounted on a carriage comprising slides 47, 48 and 49 and sleeves 50 which are adapted to slide on the guide rods 41. A rack 51 is carried by the carriage and is adapted, toward the end of the forming stroke

of the piston, to engage a pinion 52 mounted on a shaft 53 carrying the roller 33. The second roller 34 is mounted on a shaft 55 carrying a gear 56 meshing with a gear 57 on the shaft 53, so that the two rollers 33 and 34 are operated in unison as the rack 51 passes the pinion 52 during the forming stroke of the piston. The roller 33, as shown more in detail in Fig. 8, is provided with a flat surface 60 to provide clearance for the passing of the piston 35 and the shaft 53 thereof is mounted in a journal 61 which is slideable in a seat 62 and is urged toward the sealing position by means of a spring 63. The roller 34 is similarly formed. Each roller also carries a suitable latching device, not shown, which may comprise a ball detent engaging a recess in the roller to cause the roller to normally come to rest with the flat face 60 in registration with the path of the piston 35. The rollers are thus caused to make a single revolution at each actuation of the piston and when the piston is retracted remain in operative position. The brackets 23 and members 25 and 30 are similar to those described in connection with Figs. 2 to 4 and have been given the same reference characters.

At the lower end of the path of travel of the piston, 35, a suction head 68 is provided, having a perforated face 69 against which the bottom of the complete carton comes to rest at the end of the forming stroke. The interior of the head 68 communicates through a duct 70 and a valve 71 with a section line 72. The valve 71 is provided with a control arm 73 which is adapted to be engaged by a pin 74 on the slide 49. The arm 73 is adapted to open the valve 71 and apply suction to the head 68 from the line 72, when the pin 74 trips the arm 73 on the downward stroke of the piston and causes the valve 71 to cut off the suction and vent the head 68 when the pin 74 is retracted past the arm 73 on its return stroke. In this way, the vacuum produced in the head 68 causes the finished carton to adhere to the face 69 thereof while the piston is withdrawn therefrom on its return stroke. After the piston has been completely withdrawn from the carton, the arm 73 is actuated to cut off the suction and allow the carton to fall from the face 69 onto a suitable receiver.

Shutters 75 are hingedly attached to the sides of the head 68 and are adapted to be folded to engage the sides of the carton for retaining the same in shape while the carton is held on the head 68. When the suction is released, the shutters 75 are actuated to allow the completed carton to fall from the head 68. For this purpose the shutters are shown as mounted on shafts 76 and 77 carrying meshing gears 78 and 79. The shaft 76 carries a pinion 80 which engages a rack 81 attached to slide 49. The rack 81 serves to shift the shutters 75 through a 90° arc so as to fold them against the sides of the carton when the rack and piston are fully advanced and to turn the shutters parallel to the face 69 when the rack 81 and piston 35 are retracted.

In the operation of this form of the invention, a flat blank is placed upon the plate 20 and the piston 35 is actuated manually by grasping the arm 46 and pushing the piston and slides downwardly along the rods 41. The downward movement of the piston forms and folds the carton as described in connection with Figs. 2 to 4 and the completed carton is removed from the piston by the suction head 68 as above described. The piston 35 may, of course, be actuated automatically by a suitable driving means, if desired.

As the seams 17 pass the rollers, the latter are rotated by the rack 51 for sealing the seams and the shutters 75 are actuated to hold and then release the carton.

In the embodiment shown in Figs. 9 to 13, a double-acting automatic machine is illustrated. In this embodiment a web 82 is fed from a reel 83 between feed rollers 84 and is severed into sheets of the desired lengths by means of a pair of cutting knives 85. The sheet passes between two plates 20 which are of the type described above and each of which carries the folding and sealing members 25, 30, 33 and 34. The piston 35 is adapted to pass through the plates 20 first in one direction and then in the other so that alternate forming operations occur on opposite sides of the machine. At the ends of the machine are mounted vacuum heads 86 and 87, respectively, similar to the suction head 68 above described. The heads 86 and 87 are mounted on plungers 88 and 89 respectively carrying racks 90 and 91, which slide into supports 92. The rack 90 engages a pinion 93 mounted on a shaft 94 carrying a pinion 95 which engages a rack 96 on a slide 97. The rack 99 engages a pinion 98 mounted on a shaft 99 carrying a gear 100. The gear 100 meshes with a similar gear 101 mounted on a shaft 102 carrying a pinion 103 engaging a rack 104 mounted on the slide 97. The slide 97 is mounted to slide in supports 105 and is driven by a rod 106 connected to a gear 107 mounted on a shaft 108 which meshes with a pinion 109 on a shaft 110 of a driving motor 112.

A second slide 115 is attached to the slide 97 by means of a bracket 116. The slide 115 carries racks 117 and 118 which are positioned respectively to engage pinions 119 and 120 mounted on shafts 121 and 122 respectively which actuate the roller 33 as above described. The pinions 119 and 120 are preferably connected to the shafts 121 and 122 by one-way clutches so that they are actuated only during the forming stroke of the respective racks 117 and 118.

As shown in Figs. 11 to 13, the piston 35 is provided at its ends with inserts 125 and 126 respectively of magnetic material and electromagnets 127 and 128 are disposed in the contacting faces of the suction heads 86 and 87. Rows of orifices 129 and 130, through which suction is applied, are arranged around the peripheries of the electromagnets 127 and 128.

Suitable means are actuated by the plungers 88 and 89 for controlling the suction so that suction is applied to the heads 86 and 87 during the time that the heads are withdrawing the cartons from the piston 35. Switches may be actuated by the slide 97 for energizing and de-energizing the electromagnets 127 and 128 at appropriate times.

In the embodiment shown, the plungers 88 and 89 contain ducts communicating by flexible conduits 135 and 136 with control valves 137 and 138 similar to the valve 71 of Fig. 7. The valve 137 and 138 have control arms 140 and 141 actuated by spaced lugs 142, 143, and 144, 145 carried by the plungers 88 and 89 respectively. The arrangement is such that when the lugs 143 and 145 pass the arms 140 and 141 on the forming stroke, they trip the valves 137 and 138 to suction position, and when the lugs 142 and 144 pass the arms 140 and 141 on the return stroke, they trip the valves to vent position.

For controlling the electromagnets 127 and 128 a switch 150 is positioned to be actuated by lugs 151 and 152 on the slide 97. The switch

150 is a double-pole switch adapted at alternate actuations by the lugs 152 on the advance stroke (to the right) to energize first the electromagnet 127 and then the electromagnet 128 and upon actuation by the lug 151 on the return stroke (to the left) to de-energize the electromagnets. The switch 150 is actuated by the lug 152 when the slide is in position to fully advance the heads 86 and 87 toward the piston 35 and by the lug 151 when the heads 86 and 87 are in piston release positions.

It is to be understood that the above control devices for the suction heads and electromagnets are representative only and that any suitable automatic controls may be used.

In the operation of this device, beginning with the position shown in Fig. 9, the completed carton 155 has been withdrawn by the movement of the head 86 from the piston 35 and is held on the head 86 by suction. The piston is entirely free and is located to the left of the forming plates 20 so that a new blank may be inserted between the plates 20.

At the next operation as the plungers 88 and 89 and heads 86 and 87 start their return stroke (toward the center) the lug 142 shifts the valve 137 to cut off the suction from the head 86 so as to allow the folded carton 155 to drop into a suitable receptacle. As the heads 86 and 87 continue their advance, the head 86 engages the piston 35 and pushes the piston to the right, as indicated in Fig. 11, thereby forcing the next blank through the righthand plate 20 and past the forming and sealing mechanism located to the right of the plates 20.

At the extreme limit of their forward strokes, the heads 86 and 87 are both brought into engagement with the piston 35 which is then in its center position as indicated in Fig. 12. At this point, the electromagnet 128 on the head 87 is energized by the switch 150, causing the electromagnet 128 to attract the magnetic material 126 on the piston 35. As the heads are retracted on their return stroke, the electromagnet 128 causes the piston 35 to move to the right with the head 87 until it reaches a position at which the carton has been fully formed and sealed. At this point the piston is already separated from the head 86 but is still restrained by head 87 due to the action of electromagnet 128. When the electromagnet 128 is de-energized by the switch 150 owing to the action of lug 151 acting on the return stroke only, and suction is applied to the head 87 by the lug 145 tripping the arm 141, the piston 35 is released from the head 87 and only the formed carton adheres to the suction head. The piston is meanwhile immobilized. Further movement of the suction head 87 accordingly serves to withdraw the formed carton from the piston 35. The head 87 then starts to advance, the lug 144 trips the valve 138 to cut off the suction and allow the formed carton to fall from the head 87, a new blank is placed between the plates 20, and the operation is repeated, the carton in this instance being formed by movement of the piston to the left through the forming mechanism located to the left of the plates 20. It is thus seen that as the piston 35 is alternately moved to the right and left, the cartons are alternately formed and folded on the right and lefthand sides of the machine. The operation is continuous and automatic.

Although specific embodiments of the invention have been shown and described for pur-

poses of illustration, it is to be understood that various changes and modifications may be made therein as will be readily apparent to a person skilled in the art. The invention is only to be restricted in accordance with the scope of the following claims.

What is claimed is:

1. An automatic carton folding machine comprising a pair of spaced parallel plates adapted to receive a blank therebetween, said plates each having a central opening conforming to the size of the bottom of the folded carton, a piston mounted to be reciprocated through said openings, members associated with each plate in the path of said piston for folding and forming the sides and end folds of said carton as the blank is advanced by said piston, a pair of heads supported for movement along the path of travel of the piston, means reciprocating said heads toward and away from each other, electromagnets disposed in each of said heads, magnetic material disposed in the ends of said piston to cooperate with the respective electromagnets and means synchronized with the movement of said heads for controlling the energization of said electromagnets to cause each head in turn to exert a magnetic force to pull the piston and blank past the folding mechanism and then release said piston, and means to strip the folded carton from said piston and thereafter release the carton, said head on its return stroke pushing the piston to its central position.

2. An apparatus for forming folded open top cartons which are tight to a predetermined level from flat rectangular blanks, comprising a flat plate adapted to receive the blank, said plate having a rectangular opening corresponding to the bottom of the carton and defined by side edges spaced by the width of the bottom of the carton and extending beyond the length of said bottom to the full width of the blank, converging edges extending from the ends of said first edges to the ends

of said bottom and transverse edges joining said converging edges and extending along the ends of said bottom to form a pair of triangular openings at each end of said rectangular opening suited to fold side end flaps, side guide plates extending downwardly from said side edges of said first plate to receive the folded carton therebetween, and vertical inverted U-shaped end folding member attached to said transverse edges of said first plate with vertical legs depending below the surface thereof and spaced from said side plates for the passage of the side end flaps therebetween, a piston having a rectangular cross section corresponding to the bottom of said carton adapted to pass through said rectangular opening for forcing the blank therethrough and a pair of folding members mounted below each of said end folding members to fold the side end flaps against said piston for forming the ends of said carton as the piston advances, sealing means cooperating with said piston to seal the folded end flaps and means to strip the folded carton from said piston as the piston is retracted.
